UNITED STATES PATENT OFFICE.

MICHAEL D. HADJISPIRIDIS, OF NEW YORK, N. Y.

VACUUM-CLEANER.

1,019,633.

Specification of Letters Patent.

Patented Mar. 5, 1912.

Application filed April 6, 1911. Serial No. 619,238.

To all whom it may concern:

Be it known that I, MICHAEL D. HADJISPIRIDIS, a citizen of Turkey, residing at New York, county of New York, State of New York, have invented new and useful Improvements in Vacuum-Cleaners, of which the following is a specification.

This invention relates to a portable vacuum cleaning apparatus which is provided with one or more bellows pumps mounted on the device whereby particles of dust can be sucked into a tank carried by the device. The bellows pumps are secured on and located in a vertical plane with the axis of the vacuum pipe. Each pump bellows is adapted to be actuated and give oscillatory reciprocating motion in a curvilinear path at right angles to the axis of the vacuum pipe. The pumps communicate with a vacuum pipe and when operated force the air out of the said pipe and create a suction at the mouth of the nozzle thus sucking any particles of dust or dirt lying in the vicinity of the inlet nozzle into the collecting tank. The device is equipped with a stirrup having a yielding connection attached to the vacuum pipe which tends to force the mouth of the nozzle toward the floor while the device is operated.

The novel features of the invention are more fully described in the following specification and claims and illustrated in the accompanying drawings in which:

Figure 1 represents a side elevation partly in section of an apparatus embodying this invention. Fig. 2 is a detail section showing the lower valve mechanism.

In this drawing the letter *a* designates a tank having a lower inlet pipe *b* and an upper vacuum pipe *c*. The lower portion of the tank is closed by a cover *a'* which is adapted to be bolted or screwed to the tank so that the cover can be readily removed. To the lower end of the inlet pipe is attached in any suitable way a nozzle *d* adapted to communicate with the said tank.

To the upper portion of the vacuum pipe is secured a pair of bellows pumps *e* and *f* having inlet pipes *g* and *h* leading into the said vacuum pipe. The operating parts of each of these pumps is arranged in a line with the axis of the vacuum pipe and each bellows is provided with a handle *i* and *j* whereby the bellows can be manipulated. The upper end of the vacuum pipe has a handle *k* whereby the device can be carried

when not in use, or when only one pump is operated the handle can be utilized to hold and guide the device.

In the interior of the tank is placed a bag *m* with its mouth facing the lower portion of the tank. This bag is reticulated to allow the air to pass through the interstices of the fabric and is moistened so that any particles of dust will cling to the interior of the bag. The bag is covered with a porous fabric *m'* so that when the bag is jammed in place in the tank it will not be apt to shift its position. To the lower portion of the vacuum pipe is attached a spring *n* to the lower end of which is suspended a stirrup *o* adapted for the insertion of a foot so that the apparatus may be steadied at the desired angle.

Each bellows pump is equipped with one or more flap valves *p* adapted to open outwardly and allow the air to be expelled from the interior of the pipe when the pump is in operation. The lower interior portion of the vacuum pipe is provided with a valve *q* of suitable construction to normally rest on a seat *r* formed in the vacuum pipe.

The operation of the apparatus is as follows: When the pump is oscillated to compress the bellows it forces the air in the vacuum pipe out at the valve *p* the valve *q* in the meantime remains closed until the pump is again oscillated to expand or extend the bellows the air then under the valve *q* opens the valve and rushes into the pipe thus creating a suction at the mouth of the nozzle.

The parts of the device such as the tank with its pipe connections may be made of aluminum or other light metal so that the device can be carried with ease.

I claim:

1. A vacuum cleaner comprising a tank having a depending nozzle, a vacuum pipe extending upwardly from the tank, devices operatively carried by the vacuum pipe for creating a suction at the mouth of the nozzle, and steadyng means connected to the vacuum pipe adapted to force the mouth of the nozzle toward the floor.

2. A vacuum cleaner comprising a tank having a depending nozzle, a vacuum pipe extending upwardly from the tank, devices operatively carried by the vacuum pipe for creating a suction at the mouth of the nozzle, and an adjustable steadyng device depending from the vacuum pipe for engagement

with the floor adapted to yieldingly hold the nozzle against the ground.

3. A vacuum cleaner comprising a tank having a depending nozzle, a vacuum pipe 5 extending upwardly from the tank, devices operatively carried by the vacuum pipe for creating a suction at the mouth of the nozzle, a spring connected to the vacuum pipe, a stirrup suspended from the lower end of the 10 spring for engagement with the foot of an

operator and adapted to hold the nozzle against the ground.

In testimony whereof I have hereunto set my hand in the presence of two subscribing witnesses.

MICHAEL D. HADJISPIRIDIS.

Witnesses:

WILLIAM MILLER,

CHRISTIAN H. ALMSTAEDT.
